SUBLIMATING APPARATUS

Arthur Ogren, Hillsdale, N. Y.

Application July 19, 1944, Serial No. 545,718

12 Claims. (Cl. 266—19)

This invention relates to apparatus for the extraction of material from its ore by sublimation, such as the extraction of metallic magnesium from lime ore containing magnesium. The invention is especially suitable for the extraction of metallic magnesium. According to chemical reactions well known to the art, said lime ore is first mixed with other ingredients such as iron silicon salts and fluorspar. The mixture is made into briquettes about the size and shape of walnuts and placed into paper bags holding about 50 lbs. each. The bags are then pushed into a row of fixed retorts, four bags to a retort, said retorts being mounted in a gas heated furnace. With the retorts so charged, the briquettes are cooked, the magnesium coming off as a vapor which is condensed in a cooling chamber. In forcing the bags into the retorts, some of the retorts often are completely filled, so that during the cooking, the magnesium vapor is blocked from escaping forward to the cooling chamber. Because the vapor cannot escape it remains in the briquettes and is lost when the latter are cleaned out of the retorts after the cooking is completed. It requires much effort to scrape out the burned briquettes from the retorts when making them ready for a fresh charge.

In my apparatus instead of loading fixed retorts with bags of briquettes, a removable inner tube is used in the retort. The tube is loaded without the use of bags, while outside of the retort, and then inserted therein. A special carriage is provided which travels on rails running transversely of the furnace.

On the carriage is a hopper for the charge with a chute leading down therefrom for charging a tube by gravity instead of jamming bags of briquettes therein. The carriage is provided with motor driven means for inserting and withdrawing an inner tube from the retort opposite which it is set. A pivotally mounted guide is supported on the carriage for supporting a tube after it has been withdrawn. When once withdrawn, the guide with the tube on it is tilted to discharge the spent materials from it into an ash pit.

The inner tube is provided with a longitudinal slot. This, combined with the fact that the tube is first withdrawn from the retort before being charged, makes it possible to provide a perforated tubular core for the inner tube, which core insures the passage, from the tube, of the magnesium vapor during cooking to the condensing sleeve located outside of the retort in a water cooled chamber.

Whereas the apparatus has been described for

use in extracting magnesium, it will be understood that it can be used for the extraction of other materials where conditions are similar. Where the term "furnace" is used, it will be understood to include heating means of any suitable type, where consistent with the context.

Other objects and advantages will become apparent upon further study of the description and drawings in which:

10 Fig. 1 is an elevation of the device with the furnace shown in section and before the inner tube is withdrawn.

Fig. 2 is an elevation similar to that of Fig. 1, but shows the inner tube withdrawn. The discharge position of the inner tube and its support is shown in dotted lines.

Fig. 3 is an elevation of the front of the furnace with a portion omitted which elevation is taken along the line 3—3 of Fig. 1.

20 Fig. 4 is a section taken along the line 4—4 of Figs. 1 and 6.

Fig. 5 is a section taken along the line 5—5 of Figs. 1 and 6.

Fig. 6 is an elevation of the carriage shown 25 without the furnace.

Fig. 7 is a section through the retort, inner tube and cooling chamber to an enlarged scale, the sodium shield being shown in elevation.

Fig. 8 is a top plan view of the inner tube shown 30 by itself.

Fig. 9 is a section along the line 9—9 of Fig. 7.

Fig. 10 is a section along the line 10—10 of Fig. 7.

Fig. 11 is a partial section to an enlarged scale 35 showing the head of the cooling chamber and its gasket, and Fig. 12 is an end view, looking to the left in Fig. 7 of the sodium shield.

The gas furnace 13 has mounted therein a row 40 of retorts 14, only four being shown in Fig. 3, but it is customary to use twenty in a row. The retorts 14 are supported by uprights 15. Retorts 14 project from the front wall of furnace 13, the cooling and condensing chambers being located at the projecting portion as will be more fully 45 explained. Mounted in front of the furnace are rails 16 which run parallel to the front wall of furnace 13. A carriage, denoted in its entirety by the numeral 17, is mounted to run on rails 16 in front of the furnace.

50 The carriage has body members 18 upon which is mounted base plates 19, 20 and 21 for connecting them. The parts are welded together. Extending upwardly from base plate 19 are four inclined uprights 22, Figs. 4 and 6. A pair of uprights 22 supports journal 23 and the other

pair supports journal 24. Pivotedly mounted in journals 23 and 24, by means of trunnions 25 and 26, is a semi-cylindrical guide 27. Extending upward from base plate 20 are four uprights 28 which support at their upper ends a platform 29, Figs. 5 and 6. The outer end of trunnion 25 has fixedly mounted on it a lever 30. Another lever 31 is pivotally mounted on the side of platform 29. Pivotally connected to levers 30 and 31 is a link 32. When it is desired to tilt guide 27, as shown in dotted lines, Fig. 2, for a purpose to be described, lever 31 is turned manually in a counter-clockwise direction.

Rotatably mounted in blocks 33, which in turn are set on platform 29, is an idler gear 34 which engages rack 37. Also set on platform 29, are blocks 35 which support a short shaft 36. Short shaft 36, has fixedly mounted on it, gear 38, Fig. 5, which also engages rack 37. The other end of shaft 36 has fixed to it sprocket wheel 39. Extending upward from blocks 35 are supporting arms 40 which pivotally support a flanged roller 41 engaging the top of rack 37. A motor 42 is mounted on base plate 20. Gear reduction box 43, also mounted on plate 20, is driven by motor 42. Sprocket wheel 44 on box 43, is engaged by chain 45, said chain also engaging sprocket wheel 39, the rotation of which rotates gear 38. The rotation of gear 38 causes longitudinal motion of rack 37 to or from furnace 13 depending on the direction of rotation of said gear. Also on gear box 43 and driven from motor 42, is sprocket wheel 46.

Body members 18 of carriage 17 have two pairs of cross bars 47 extending between and below them and welded to them. Between the members of each pair of cross bars 47, is rotatably supported a pair of track rollers 48, the latter running on rails 16. A pair of rollers 48 is supported on each axle 49. On one of the axles 49, Figs. 5 and 6, is fixedly mounted sprocket wheel 50. A chain 51 engages sprocket wheel 50 and sprocket wheel 46 on gear box 43. The rotation of sprocket wheel 50 causes the travel of carriage 17 along the front of furnace 13.

Extending upward from base plate 21 are uprights 52 which support a guide sleeve 53, the latter acting as a guide for rack 37 as it is moved to and from furnace 13.

In conjunction with gear box 43, are the controls, not shown, by which the direction of rotations and their actuation of sprocket wheels 44 and 46 are controlled for the motions of rack 37 and the travel of carriage 17.

In furnace 13 are supported by posts 15 and the front wall of the furnace, a row of retorts 14, four of them being shown in Fig. 3. The forward end of each retort projects out of furnace 13, the projecting portion forming a cooling chamber, a shell 56 being welded to said portion to form a water jacket 59, water being led in through tube 57 and discharged from tube 58. Inside of retort 14, at its cooling chamber portion opposite water jacket 59 is condensing cylinder 60, upon the inside of which the metallic magnesium is condensed, said cylinder being readily removable from the retort. In front of cylinder 60 is mounted a cylindrical cap 61, known in the art as a sodium shield which collects sodium products from the vapor reaching the cooling chamber. The outside surface of cap 61 is serrated, Fig. 12. The forward end of each retort 14, is provided with an annular flange 62 flaring out therefrom. Flange 62 has an annular ridge or tongue 63 projecting therefrom,

Figs. 7 and 11. A head 64, provided with a groove in which is located gasket 65 seals off the front of the retort. Head 64 is held on by air pressure due to the suction created in retort 14 by the withdrawal of air therefrom through tube 66, the latter being connected to a suction pump, not shown.

Inside each retort 14 is an inner tube 67 removably mounted therein. Tube 67 is provided with a longitudinal slot 68. The rear of tube 67 is beveled off at 69. The forward end of tube 67 has a heat shield 70 welded to it. Projecting from the rear of shield 70, opposite a hole through the shield, is a perforated tube or core 72, supported substantially at the axis of the inner tube by short posts 73.

In operation, after cooking the charge held in the inner tube for about eight to nine hours, said inner tube 67 is withdrawn from a retort 14 by the movement of rack 37 away from the front of furnace 13 after hook 74 on the rear end of rack 37 has been brought into engagement with ring 71 on heat shield 70. Before removing inner tube 67, the suction through tube 66 was stopped permitting the removal of head 64. Also condensing cylinder 60 and sodium shield 61 were removed. The movement of rack 37 away from the furnace is effected by setting the controls so that sprocket wheel 44 rotates in a clockwise direction, Fig. 6. This rotates sprocket wheel 39 on shaft 36 and with it gear 38 which latter engages the teeth of rack 37. Rack 37 is thus moved to the position shown for it in Fig. 2, sliding through guide 27 and through guide sleeve 53. The bore of sleeve 53 is rectangular. Idler gear 34 also supports rack 37 in its motion, while flanged roller 41 helps maintain the rack against tilting sidewise and holds it down against gear 38. Such tilting is also prevented by the rectangular bore of sleeve 53. When rack 37 is withdrawn from the furnace, inner tube 67 is brought into position to be supported by semi-cylindrical guide 27. To prevent dislodgement of inner tube 67 from guide 27, a manually operated catch 77 is provided which passes through guide 27 into engagement with said inner tube.

When once inner tube 67 is withdrawn and locked in guide 27 by catch 77, in order to dump its residue into ash pit 78, it is tilted by tilting guide 27 as shown in dotted lines in Fig. 2. The tilting is effected by manually moving levers 30 and 31 and link 32 as shown by the dotted lines until the tilting is sufficient to empty tube 67. Before tilting, hook 74 was disengaged from ring 71. After being emptied, tube 67 is restored, together with guide 27, to horizontal position by properly manipulating levers 30 and 31 and link 32. A hopper 79, containing fresh material, is mounted by means of uprights 80, so that spout 81 is in line with slot 68. In order to fill a tube 67 with a fresh charge, a gate, not shown, is opened in spout 81 so that the material begins to spill therefrom, and at the same time, the controls at the gear box 43 are so manipulated that the rack moves toward the furnace, gradually moving said tube when connected thereto into retort 14 with its slot 68 passing in line under spout 81. Condensing cylinder 60 and sodium shield 61 are placed in the retort and head 64 applied to flange 62. Head 64 is held on flange 62 by suction applied through tube 66 at first by means of a roughing pump, not shown, to remove impurities and then by a diffusion pump, also not shown. The diffusion pump is used

merely to build up a vacuum and hold it during the cooking and not for the purpose of drawing off gaseous impurities as with the roughing pump. The use of these pumps is well known to the art.

With the charged inner tube 67 placed back in the retort 14, it is cooked for eight to nine hours, the magnesium vapor released by the cooking passing through the perforations in tube 72 and the opening in heat shield 70 opposite tube 72. Other openings 82 are provided in heat shield 70 through which vapor also passes. From the openings in heat shield 70 the vapor passes into the cooling chamber portion of retort 14 where it condenses on the inside of cylinder 60.

When the cooking of the charge in another retort 14 is completed, carriage 17 is moved along rails 16 to a position opposite said second retort and the operations just described for a previous retort are repeated on the second retort.

In the claims, the expression "for the extraction of metal from its ore by sublimation" is used, but it is intended to be broad enough to cover other materials capable of being extracted by the process of sublimation described.

The rear end of inner tube 67 is sloped off at an inclination substantially equal to the angle of repose or sliding of the charge to prevent the latter from spilling out.

I claim:

1. An apparatus for the extraction of metal from its ore by sublimation, comprising a furnace, a plurality of retorts mounted in a transverse row in the furnace, an inner tube, removably mounted in each retort, for receiving a charge of the ore and other materials for the extraction of the metal, a carriage mounted to travel only transversely in front of the retorts, mechanism on said carriage for withdrawing the tubes from the retorts and pushing them in again, and guide means on the carriage for supporting a tube when withdrawn from its retort said guide means being mounted on the carriage to remain always outside of the retorts.

2. An apparatus for the extraction of metal from its ore by sublimation, comprising a furnace, a retort mounted in the furnace, an inner tube removably mounted in the retort for holding a charge of ore and other materials for the extraction of the metal, mechanism mounted outside of the furnace in front of the retort for withdrawing the tube from the retort and pushing it in again and tiltably mounted guide means for receiving the tube when it is withdrawn, said means with the tube being tilted when the latter is withdrawn for discharging the spent charge from the tube.

3. In an apparatus, for the extraction of metal from its ore, by sublimation, having a retort and means for heating the retort, an inner tube mounted in the retort and removable through the forward end of the latter, for holding a charge of ore and other material for the extraction of the metal and a foraminous tubular core mounted in said tube extending for substantially the length thereof.

4. In an apparatus, for the extraction of metal from its ore by sublimation, having a substantially horizontal retort, and means for heating the retort, an inner tube mounted in the retort and removable through the forward end of the latter, for receiving a charge of the ore and other materials for the extraction of the metal, a closure for the forward end of the tube to prevent spilling of the charge from said end, said tube having a longitudinal slot at its top extending

from the closure to its rear end, the rear end of the tube being open and inclined, extending down from the slot at the top of the tube and rearward, permitting the charge to assume its natural slope without spilling from the rear of the tube.

5. An apparatus for the extraction of metal from its ore by sublimation, comprising a furnace, a retort mounted in the furnace, an inner tube mounted in the retort and withdrawable through the forward end of the latter for receiving a charge of the ore and other materials for the extraction of the metal, said tube being adapted to permit the discharge of the charge from its rear end when sufficiently tilted and mechanism for withdrawing the tube from the retort through the forward end of the latter and tilting it to discharge the charge from its rear end.
- 10 6. In an apparatus for the extraction of metal from its ore by sublimation, a furnace, a plurality of retorts mounted in a transverse row in the furnace, inner tubes, each provided with a longitudinal slot, mounted in the retorts with the slot upward and removable through the forward end of the latter, said tubes adapted to hold the charges of the ore and other materials for the extraction of the metal, a carriage mounted to travel only transversely in front of the retorts, mechanism on the carriage releasably engaging the tubes for pulling them out of and pushing them into the retorts, guide means on the carriage for supporting a tube when withdrawn from its retort, said guide means being mounted on the carriage to remain always outside of the retorts, and a hopper on the carriage with its discharge outlet over the guide means for delivering a charge to a tube through its slot when the tube has been pulled out of its retort.
- 25 7. In an apparatus, for the extraction of metal from its ore by sublimation, having a retort and means for heating the retort, an inner tube removably mounted in the retort for holding a charge of ore and other materials for the extraction of the metal, said tube being provided with a closure at its forward end and open at the other, said tube also having a longitudinal slot extending substantially from the closure to its open end.
- 30 8. In an apparatus, for the extraction of metal from its ore by sublimation, having a retort and means for heating the retort, an inner tube removably mounted in the retort for holding a charge of ore and other materials for the extraction of the metal, a heat shield attached to one end of the tube and a tubular member in said tube, said member having a foraminous wall for substantially the length of the member, the member extending for substantially the length of the tube into contact with the shield, the latter having an opening through it opposite the contacting end of said member.
- 35 9. In an apparatus, for the extraction of metal from its ore by sublimation, having a retort and means for heating the retort, an inner tube removably mounted in the retort for holding a charge of ore and other materials for the extraction of the metal, a heat shield attached to one end of the tube and means on the heat shield suitable for releasable engagement therewith for the removal of the tube.
- 40 10. An apparatus for the extraction of metal from its ore by sublimation, comprising a furnace, a retort mounted in the furnace, an inner tube, provided with a longitudinal slot for sub-

stantially its length, removably mounted in the retort, said tube being adapted to hold a charge of ore and other materials for the extraction of the metal, being withdrawn from the retort for the discharge of its charge when spent, a hopper mounted outside of the furnace in front of the retort for delivering a charge to the tube through its slot and mechanism for returning the tube into the retort with the slot of the tube passing under the discharge end of the hopper as the tube is being returned.

11. In an apparatus, for the extraction of metal from its ore, having a substantially horizontal retort, and means for heating the retort, an inner tube mounted in the retort and removable through the forward end of the latter for receiving a charge of the ore and other materials for the extraction of the metal, a heat shield closing off the forward end of the tube except for

one or more vents in said shield, the rear end of the tube being open, engageable means on the heat shield and mechanism releasably engaging the engageable means for withdrawing the tube from the retort through the forward end of the latter and pushing it in again.

12. An apparatus for the extraction of metal from its ore, comprising a retort, means for heating the retort, an inner tube removably mounted in the retort, said tube being adapted to hold a charge of ore and other materials for the extraction of the metal, mechanism for withdrawing the tube from the retort for the discharge of its charge when spent and for returning the tube into the retort when it has been recharged, and means for delivering a charge to the tube during the time it is moving into the retort for its return.

ARTHUR OGREN.
